US0D1001911S

(12) **United States Design Patent** (10) Patent No.: **US D1,001,911 S**
(45) Date of Patent: ** Oct. 17, 2023

(54) **TOY CONSTRUCTION ELEMENT**

(71) Applicant: **Jarola Vision B.V.**, Lutten (NL)

(72) Inventor: **Gerrit Jan De Wilde**, Anerveen (NL)

(73) Assignee: **Jarola Vision B.V.**, Lutten (NL)

(**) Term: **15 Years**

(21) Appl. No.: **29/749,683**

(22) Filed: **Sep. 8, 2020**
